GAME

Richard R. Vensel, Mount Lebanon Township, Allegheny County, Pa. (740 Washington Road, Pittsburgh 28, Pa.)

Filed Nov. 23, 1962, Ser. No. 239,643
4 Claims. (Cl. 273—95)

This invention relates generally to games, and more particularly to a game of skill which involves the manipulation by magnetic force of magnetic missiles with relation to movable hollow-walled bodies having apertures through which the missiles are directed.

Game devices of the character to which this invention relates have heretofore been provided in which the player, holding a magnet above a transparent membrane, suspends a steel ball against the underside thereof and by moving the magnet travels the ball from a starting position to a position over a target and then releases the ball by withdrawing the magnet and letting the ball drop, endeavoring thereby to drop the ball into or onto the target.

According to the present invention, I provide in a toy of this general kind unique movable targets and particularly targets that move or roll erratically and with motions that are difficult for the operator to control. A combination of conditions is thereby provided that increases the action of the game and requires more skill on the part of the player than games having fixed targets. Much of the fascination of a game such as this depends on the ability of the player, either by skill or chance to maneuver the target and the missiles into a relation where the missile can be dropped into the target and still not lose from another target a ball or missile that may have previously been dropped therein. To get the several missiles in the several targets in a minimum length of time gives the player a gratifying sense of achievement, as with the solving of a puzzle, and enables players using a watch or miniature hour glass to contest their skill and to follow a scoring system.

A principal object of the invention therefore is to provide a game which furnishes action and challenges the skill of the player by having targets, the motions of which are not entirely within the control of the player.

Another object is the provision of a game of small compact design capable of being held in a player's hand and which offers a substantial challenge in its successful or winning operation by a player.

Still another object is to provide a game having a free moving missile controllable in direction and movement by a magnet manipulated by the player for the purpose of directing the missile against a movable target.

A complete understanding of the invention may be had from the following detailed description of a specific embodiment thereof when read in conjunction with the appended drawings, wherein:

FIG. 1 is a front elevational view of the game, partly broken away;

FIG. 2 is a plan view of the game; and

FIG. 3 shows in perspective view one of the targets of the game in detail.

Referring now to the drawings, wherein like reference characters designate like or corresponding parts throughout the several views, there is shown in FIG. 1, which illustrates a preferred embodiment, the completely assembled game 11. The game 11 as shown in FIGS. 1 and 2 is composed preferably of a circular base 12 of sheet card stock or other material which is non-magnetic, and the base is covered on its upper surface 13 by a transparent cover or dome 14 which is hemispherical in shape and of a material which is also non-magnetic. The pe-

2

riphery of the dome 14 is provided with a bell flange 14a which is continuous, and which is fastened to the peripheral marginal portion of the base 12 by suitable fasteners such as rivets 15.

5 A magnet holder 16 is shown in FIG. 1 to include a body 17 of a size to be grasped by a player not unlike a knob and the body is provided with a longitudinal bore 18 within which an elongated permanent magnet 19 is force-fitted with the magnet being exposed at one end of the holder 16 for a purpose to be explained hereinafter. The magnet preferably is tapered in diameter such that one end of a flexible keeper or cord 21 may be wedged between the magnet and bore wall of the longitudinal bore 18. The other end of the cord 21 is connected to the lower surface 22 of the base 12 by suitable fastener means such as the headed anchor member 23. In this fashion the holder 16 is readily available to the players, may be freely moved in the range required and is less likely to be lost.

10 In FIGS. 2 and 3, 24 designates each of a plurality of hollow, non-magnetic targets which may simulate a nut such as an English walnut or similar somewhat irregularly shaped object, and which is provided with an aperture 25 therein. In practice, it has been found best to provide the target with a peripheral flange 26 in a plane perpendicular to the axis of the aperture 25. The flange 26 functions to aid a player in maintaining the target 24 with its aperture side facing upwardly as depicted in FIG. 1, for example, because the flange prevents the target from rolling excessively, but none-the-less with an erratic and unpredictable motion. The targets 24 move freely on the upper surface 13 of the base 12 and beneath the dome 14. A soft molded plastic target has been utilized for the example of the invention described herein, although other non-magnetic materials may be suitably fabricated and fashioned in the desired configuration.

15 The height of the dome 14 in the modification of the invention illustrated by FIGS. 1 and 2 is equal to the radius R, FIG. 2, which extends from the center of the circular base 12 to the inner edge of the flange 14a. By this dimensioning of the dome, a uniformly-curved surface is provided over which the magnet 19 may be slidably moved. Both the inner and the outer walls of the transparent dome 14 are smooth, for example, and the wall is only as thick as is necessary to hold its form and not be readily crushed.

20 Small magnetic missiles such as the metallic spheroids 27 are influenced by the magnet 19 when the latter is in the vicinity of the spheroid such that movement of the magnet 19 on the outer surface of the dome 14 simultaneously moves a spheroid 27 captured in the magnetic field of the magnet as illustrated best in FIG. 1. The removal of the magnet 19 from the dome 14 enlarges the gap between the magnet and the ball so that the spheroid falls by gravity from its position formerly held under the influence of the magnet. A plurality of apertures 28 extend through the base 12 and are of a diameter slightly less than that of the spheroids 27 which may be removably contained within the apertures 28 in a rest condition.

25 As mentioned hereinabove, the targets 24 are freely and preferably erratically movable over the upper surface 13 of the base 12 beneath the dome 14; consequently, the object of the game is to drop or direct a missile 27 through an aperture 25 provided in a target 24. This objective is accomplished by the manipulation, with the force of a magnet, of a missile 27 from its position of rest within the base aperture 28 to an elevated position above the base and against the dome inner surface. Tilting of the game base 12 by the player places the aperture 25 of the target in upright position. The player quickly

removes the magnet 19 from its contact against the dome and consequently its holding contact with a spheroid 27 when the missile is aligned instantaneously with an aperture 25 of a target 24. The sudden release of the spheroid 27 causes it to drop by gravity toward and into the hollow interior of a target 24 through the aperture 25 thereof.

Once a spheroid 27 is contained successfully within a target 24 it must be retained in this condition until all the remaining missiles or spheroids are directed into corresponding apertures 25 of other targets 24. When all missiles are contained within all targets, one missile in each target, the player has succeeded in winning the game. Other rules of the game may, of course, be defined without departing from the spirit and scope of this invention, the sequence of operations aforementioned merely being exemplary of one manner in which the game may be played. It is important to note, however, that when a condition arises by which one target 24 contains a spheroid 27, and a subsequent target 24 is being manipulated by tilting of the base 12 simultaneously with movement of a spheroid 27 by the magnet holder 16, the chances of the game are multiplied. That is, the target containing the spheroid 27 must retain that missile while the game base is being tilted and otherwise moved to present a target aperture to a position into which a missile may be dropped. The filled targets are emptied of the missiles by more or less vigorously shaking the toy or game and the emptying takes place most rapidly when the dome is inverted.

It is manifest that the above-described embodiment of the invention is merely illustrative and that numerous modifications may be made within the spirit and scope of the invention.

What is claimed is:

1. A game comprising a non-magnetic base, a transparent non-magnetic cover overlying the base, a hollow free-rolling non-magnetic target supported on the base and free to roll about over the base under the cover, a magnetic missile positioned under the cover, and a magnet outside the cover and movable over its outer surface for attracting the missile on the inner surface of the cover opposite the magnet, the magnetic force of the magnet retaining the missile on the inner surface of the cover

and above the base as the magnet is moved on the cover outer surface, removal of the magnet from the outer surface of the cover terminating the force of attraction of the missile to the magnet whereby the missile drops toward the base and a target, the target having an opening therein large enough for the missile to fall through it and be received inside the target.

2. A game as in claim 1 wherein the base is planar and the cover is dome-shaped.

3. In a game having a non-magnetic base, a transparent non-magnetic cover overlying the base and attached at its periphery to the base, a plurality of magnetic missiles confined between the cover and the base and which may be attracted and moved about over the inside of the cover by a magnet held against the cover and released by removal of the magnet away from the cover, a plurality of hollow targets also confined between the cover and the base, each of the targets being of hollow irregular ovoidal shape and being rollable about over the base under the cover, each of the targets having an opening therein of a size to receive one of the missiles, whereby upon tilting of the base the targets have an erratic rolling motion by which the opening can be brought to a position where it is turned upwardly after which a missile manipulated by the magnet may be dropped toward the target.

4. A game as defined in claim 3 in which each target is of the shape and size of an English walnut and has a ribbed surface.
